UNITED STATES PATENT OFFICE.

EMIL CORNELY, OF PARIS, FRANCE.

FEED-MOTION FOR SEWING OR EMBROIDERING MACHINES.

SPECIFICATION forming part of Letters Patent No. 336,554, dated February 23, 1886.

Application filed August 17, 1885. Serial No. 174,617. (No model.)

To all whom it may concern:

Be it known that I, EMIL CORNELY, of Washington, District of Columbia, a resident of Paris, in the Republic of France, have invented a new and useful Improvement in Universal Feed - Motions of Sewing or Embroidering Machines, which is fully set forth in the following specification.

The feed-motion ordinarily employed heretofore in universal-feed machines consists in an upper feed-bar, which presses the cloth upon the cloth-plate, while the horizontal motion of its feed takes place. That kind of feed is sufficiently perfect for the ordinary purposes of embroidering work on a single cloth; but in certain cases the friction of the cloth upon the cloth-plate causes great inconveniences, which prevent the proper working of the machine. Thus, for instance, when two layers of cloth are to be worked, or in working with braid, cord, beads, or with metallic threads or cords, the feed is frequently different in the cloth, which slides on the plate, than in the other material which is worked upon it, and thus the entire work becomes irregular and imperfect. The pressure, also, of the feed-surface upon the cloth must be a very considerable one to produce a sliding feed, and thus delicate and fragile material—such as velvet or beads—are frequently spoiled by passing through the machine.

To overcome these difficulties I have invented a feed in which two feed-surfaces—one above and one below the cloth—act simultaneously on both sides of the cloth, and can feed the material in any direction as is required in universal embroidering and sewing machines. A feed mechanism of this general nature has been heretofore devised for use in a quilting-machine in which a lower plate is connected with rods which operate the feed-bar, so that the lower plate partakes of all the lateral motions of the feed-bar. This construction or mode of operating the under feed-surface is not, however, available for, or at least not well adapted to, ordinary sewing and embroidering machines, or for the well-known "Bonnaz" machine.

The present invention consists in the combination, with the upper feed-surface of the universal-feed sewing-machine, of a lower feed

surface or plate movable in all directions, to follow the motion of the upper feed-surface by its pressure thereon, and suitable means—a spring, for example—for returning the lower feed surface or plate to a central position when relieved of pressure. The necessity of a mechanical connection (which in ordinary machines would have to be made in a circuitous manner through the goose-neck or arm) for communicating the lateral motions from the universal feed-bar to the lower feed-surface is thus avoided.

The invention also consists in the combination, with the upper feed-surface of a universal-feed sewing-machine and the mechanism for controlling the direction of the feed thereof, of a lower feed surface or plate connected with the controlling mechanism independently of upper feed-bar, and the mechanism for imparting lateral motion to the same. The necessary agreement in direction of movement of the two feed-surfaces is thus secured by their connection with each other through the controlling mechanism, which extends or may extend from under the work-plate through the goose-neck, as in the Bonnaz machine. It will be observed that this mechanism does not convey the lateral motions of one feed-surface to the other, like the connection in the quilting-machine referred to, but determines simply an agreement in direction of the feed-motions. Other means are used to give motion to the under feed surface, the latter, preferably, being carried with the upper feed-surface by its pressure thereon and returned by a spring.

The invention further comprises certain special constructions and combinations of parts, as hereinafter set forth.

In the drawings, Figure 1 represents a vertical section through the mechanism of said feed-motion. Fig. 2 represents a horizontal view, and Figs. 3 and 4 cross-sections of a part of the mechanism shown in Fig. 1, the feed-surfaces in Fig. 4 being moreover slightly different from what is represented in Figs. 1 and 2.

A represents the feed-bar and the feed-surface of a universal embroidering-machine; B, the cloth-plate; C, the oscillating looper, which turns within the casting D, and which

is operated in the well-known manner by means of the screw-gear from rod L. The hub *a* of a toothed wheel, E, is sunk into the casting D, and can turn therein freely. A plate, 5 *b*, is adjusted within the crown of the wheel E, so that it can slide horizontally within slide-ways *p*. (Represented in Figs. 2, 3, and 4.) This plate *b* constitutes the lower feed-surface, which, as well as the upper feed-surface, A, 10 may either be covered with india-rubber, Figs. 1, 2, and 3, or it may be provided with teeth, Fig. 4. The plate *b* is secured to a small truck, which is provided with rollers or wheels *d*, which can roll on the bottom of the cavity of 15 wheel E. When the feed-bar A is pressed downward, it will strike the feed-surface of plate *b*, and will carry it along in its horizontal feed-motion, and as the cloth is thus held between the two feed-surfaces A and *b* they 20 act simultaneously upon it like the jaws of a pair of pliers, and they draw the cloth along in the direction of the feed without causing any friction thereon, and the pressure of the feed-surfaces on the material can be much less 25 than the one employed heretofore.

The crank-handle G, which is used in these kinds of machines for guiding the universal feed and the other organs of the machine in the well-known manner, is also employed for 30 guiding the lower feed-surface, *b*. This is done by means of the pinions M N O, rod L, nut *m*, sleeve P, pinions H I, and wheels K E, whereby the latter is turned in conformity with the direction of the upper feed-surface, 35 A; but as the lower feed-surface, *b*, slides within the ways *p* in the wheel E its line of movement will always be identical with that of the upper feed, A, and thus both of them will work together in any direction, according 40 to the one indicated by crank G. When the upper feed, A, rises, the lower feed becomes free and returns to its former position by the pressure of one of the springs *g*, and it is thus ready for the next operation.

45 In the center of the lower feed-surface, *b*, is a hollow space, into which extends the needle-plate *h*, into which descends the needle and upon which the nipple of the machine strikes. This needle-plate has the shape 50 shown in Fig. 3, and it is secured within the hollow part of the wheel E.

It is evident that the construction of the lower feed-plate, *b*, can be much modified. It may move within the slides *p* of the wheel E without employing the friction-rollers *d*, or 55 it may be attached to said wheel by means of hinges, or it may be secured to a universal joint, by means of which it can follow the movement of the upper feed, A, without employing the wheel E, which in this case could 60 be entirely dispensed with. I therefore do not limit my invention to the construction herein described.

I claim—

1. In combination with the upper feed-surface of a universal-feed sewing or embroidering machine, a lower feed plate or surface movable in all directions to follow the motion of the upper feed-surface by its pressure thereon, and means—such as a spring—for returning the lower feed-surface to a central position, no matter in what direction it may have been moved, substantially as described. 65

2. In combination with the upper feed-surface and feed-controlling mechanism of a 70 universal-feed sewing or embroidering machine, the wheel connected with said controlling mechanism, and the lower feed plate or surface guided by said wheel, substantially as described. 75

3. The combination, with the mechanism for controlling the direction of the feed-motion in a universal-feed sewing-machine, of the upper and lower universal-feeding surfaces connected with said controlling mechanism 85 independently of each other, substantially as described. 80

4. The combination, with the needle-plate of the shape shown, of the lower movable feeding-surface having a space in the middle 90 into which the upper part of the needle-plate extends, substantially as described.

In testimony whereof I have signed this specification in the presence of two subscribing witnesses.

E. CORNELY.
